DECORATIVE WALL SWITCH PLATE

Charles J. Goeske, Henryetta, Okla.

Application December 19, 1956, Serial No. 44,257

Term of patent 14 years

(Cl. D26—13)

Fig. 1 is a front elevational view of a decorative wall switch plate, showing my new design; and
Fig. 2 is a top plan view thereof.

A portion of the drawing figures is diagonally lined to indicate transparency.

I claim:

The ornamental design for a decorative wall switch plate, as shown and described.
